VALVE MECHANISM.

No. 909,304.

Specification of Letters Patent. Patented Jan. 12, 1909.

Application filed November 17, 1904. Serial No. 233,127.

To all whom it may concern:

Be it known that we, LOUIS ILLMER, Jr., and EDWARD J. KUNZE, both citizens of the United States, and residents of the city of New York, borough of Manhattan, in the county of New York and State of New York, have invented a new and Improved Valve Mechanism, of which the following is a full, clear, and exact description.

Our present invention relates to certain improvements in means for operating valves by fluid pressure. It is especially intended for use in connection with internal combustion engines, but it is applicable to other uses, as will fully appear hereinafter to persons skilled in the art.

Primarily the object of the invention is to provide a fully controllable means for imparting to the valve or valves rapid and certain movement terminating quickly yet without knocks or jars, and this at a minimum expenditure of energy.

Reference is had to the accompanying drawings which illustrate as examples various forms of our invention, in which drawings like characters of reference indicate like parts in the several views, and in which—

Figure 1 is a one-half longitudinal section of a valve and housing, the valve sliding longitudinally of a piston or other rod and having our improved operating mechanism applied thereto; Fig. 2 is a one-half outer end elevation of the parts shown in Fig. 1; Fig. 3 is a sectional view showing a valve and its operating means, and also illustrating devices for controlling the compression which we employ to check the valve movement at or near the end of its stroke, or at any other point along its travel, as may be desired.

In Figs. 1 and 2 only one-half of the structure is illustrated, the structure being divided on the broken line X of these views, and it will be understood that the parts omitted are identical with those illustrated.

10 indicates a rod which, in the event that the invention is applied to an internal combustion engine, may be taken to be the piston rod, and 11 the valve which in the present instance is shown as annular in form and encircling the piston rod.

12 indicates the valve housing which has an outer or main wall connected at its outer edge by a web 14 to an inner tubular wall or

sleeve 15. Said sleeve has a pocket 15^a in its outer portion, in which is fitted a stuffing box 16, carrying packing 17 for the rod 10 and a gland 18. The valve 11 has a tubular stem 19 loosely inclosing but not actually contacting with the rod. This stem is slidably fitted in the inner part 15^b of the sleeve 15, a tight connection being effected by a packing 20, which has a gland 21 bearing against it, as shown. By removing the stuffing box 16 the gland 21 may be reached and adjusted whenever desired. The valve 11 carries a tubular skirt 22, which fits loosely over the inner extremity of the sleeve 15 and moves with the valve, this skirt serving to maintain as nearly as possible a uniform passage for the air and gas or other working fluid through the housing 12. The broken lines 23 in Fig. 1 and the full lines in Fig. 2 indicate an orifice in the outer or main walls of the housing through which said fluid is introduced.

Formed integral with or fastened to the housing, one at the upper and one at the lower side thereof, are a plurality of cylinders 24, one of which is illustrated in the drawings. We prefer to provide a plurality of cylinders distributed equidistant around the housing so as to equalize the valve operating strains. This, however, is not essential to our invention, and one cylinder may be employed if desired. In each cylinder 24 a valve-actuating piston 25 is arranged, these pistons having rods 26 attached thereto which pass through stuffing boxes 27 in the inner heads of the cylinders and through the valve-housings, as shown, the inner ends of the rods being fastened by any desired means to the outer side of the valve 11. Movement of the actuating piston 25 back and forth in the cylinder 24 will, by this direct mechanical connection, actuate the valve. The piston 25 is provided with two ports 28 therein. These ports are in line with each other longitudinally of the piston, and extend from the middle portion of the piston respectively to and through the heads thereof so as to open at the ends of the piston. The cylinder 24 is provided with two admission ports 29 and two exhaust ports 30. Of these ports the admission ports 29 are located nearer the middle of the cylinder, and in such position as to respectively register

with the piston-ports 28 when the piston is at one end or the other of its stroke.

31 indicates an adjustable stop for positively limiting the leftward movement of the 5 piston 25.

In Fig. 1 it will be seen that the piston is shown at the end of its outward or rightward stroke, in which case the right-hand admission-port 29 registers with the right-hand 10 piston-port 28. It may also be seen from this view that when the piston 25 is at the end of its outward stroke, the inner end or head of the piston clears the inner exhaust-port 30, the inner admission-port 29 being 15 blanked by the imperforate part of the piston-surface. In this position motive-fluid will be admitted into the right-hand end of the cylinder 24, causing the actuating-piston to move inward or leftward and beginning 20 the opening movement of the valve 11. After the inner end of the piston 25 passes the inner exhaust-port 30, compression begins in the inner end of the cylinder 24, this compression resisting the inward movement of 25 the piston and gradually increasing until it retards or arrests the movement of the piston. By proper proportionment of the areas and by devices which will be hereinafter described, this compression may be regulated 30 and controlled so as to bring the valve to rest at any desired point. When the piston 25 reaches its leftward position and the valve 11 is opened, or shortly before this time, the left-hand port 28 registers with the 35 left-hand exhaust-port 30 and compression is relieved at the left-hand side of the actuator-piston. The compressed air on the other side of the piston is still active, however, and the piston and valve are thus held 40 at their new positions, essentially as explained in our co-pending application, Serial No. 213,815. At the end of this leftward movement of the piston, the piston will be in a position reverse to that shown in the 45 drawings, and upon supplying pressure through the inner or left-hand admission-port 29 a return movement of the piston will begin, followed by compression at the right-hand end and subsequent relief thereof, all 50 as before explained. It will also appear from the drawings that upon the beginning of the above-described leftward movement of the actuating-piston, the pressure will be continually supplied through the outer ports 55 29 and 28 until the port 28 passes the port 29. The pressure will now be cut off and the further movement of the piston leftward will be under the expansive action of the compressed fluid employed, this expansion continuing 60 the piston movement until the compression at the other end sufficiently retards or actually arrests the piston. This arrangement of the ports 28 enables the supply of fluid pressure to be cut off by the movement of 65 the piston itself, as contradistinguished from

a separate valve, and it enables us to operate the valve quickly at all speeds under the normal, or that for which it was designed. The means controlling the fluid pressure supply to the cylinder 24 need, therefore, simply 70 control the pressure only for starting the piston movement, the cut-off of the fluid pressure being dependent not upon the action of those means but upon the position of the piston itself.

Each cylinder 24 is provided with a casing 32 containing a pilot valve for controlling the fluid movement in the ports 29 and 30. This valve, as here shown, comprises two piston-like parts 33 connected by a spacer 80 34. 35 indicates a stem through which the movements are imparted to the pilot valve. The casing 32 has an opening 36 communicating with the fluid pressure supply, and with two openings 37 adapted to carry off 85 the exhaust, the opening 36 being located in the middle portion of the casing 32, and the exhaust openings 37 respectively at its ends. When the pilot valve is in its rightward position corresponding to the rightward 90 position of the actuating piston, as Fig. 1 illustrates, the outer or right-hand exhaust port 30 will be blanked by the valve and the pressure supply port 36 will be placed in communication with the outer or right hand admission port 29 of the cylinder 24. The parts being in this position, the above described rightward or inward movement of the actuating piston will take place, and the piston will be brought to rest by the compression as before described. The piston will then remain inactive until the pilot valve is shifted, uncovering the right hand exhaust port 30 and the left hand or inner admission port 29. Fluid pressure will then 100 be admitted in the left hand or inner end of the cylinder 24 and the actuating piston will be returned to the position shown in the drawings. It will be observed, therefore, that upon each change in the position of the 110 pilot valve a movement of the actuating piston 25 and the attached valve 11 is brought about, the parts 25 and 11 remaining in the new position until a second change in the 115 position of the pilot valve.

Various means may be employed for actuating the pilot valve. This will depend largely upon the use to which the invention is put. In applying the invention to an internal combustion engine we prefer to actuate the pilot valve or valves by means of cams connected to the engine cross head. One of these cams is indicated by the broken lines 38 in Fig. 2, and said cams are adapted to actuate elbow levers 39, the elbow levers 120 39 having suitable connection with the stems 35 before described.

In Fig. 3 the invention is illustrated as applied to a valve 11^a, there shown as a pump valve. This may be assumed to be a 130

valve in a mechanism of any sort. In said figure, 25^a indicates the actuating piston, and 34^a the pilot valve, both of which are essentially the same as the parts before described 5 and operate respectively in a cylinder 24^a and casing 32^a, also essentially the same as those described. With this arrangement the valve 11^a is connected to the actuating piston by a rod-like stem 19^a, as shown. 10 The pilot valve in this construction may be operated by any suitable or desired means connected with its stem.

We have before described the operation of the actuating piston and its retardment or 15 actual arrest by compression developed at the end opposite the end on which the fluid pressure is being exerted. Various means may be employed for controlling or varying this compression. According to the example given in Fig. 3, we provide two auxiliary clearance spaces 40, preferably in the form of chambers cast in the walls of the cylinder 24^a. These chambers 40 are respectively in connection with the ends of the cylinder 24^a 20 by means of pipes 41 provided with valves 42 for throttling the fluid movement. Each auxiliary clearance space or chamber 40 is also provided with a valve 43, by means of which the chambers may be vented to facilitate starting the movement of the actuating piston. By the operation of the throttling valves 42 the flow of the fluid during this compression into the auxiliary chambers 40 may be increased or diminished at will, and 25 in this manner the resistance offered to the movement of the actuating piston by the compression in the cylinder 24^a may be regulated exactly, thus causing the actuating piston to operate precisely as desired. In 30 order to prevent the compression pressure referred to from rising too high we provide each end of the actuating cylinder 24^a with a passage 44, these passages leading to the pressure-supply and being controlled by 35 check-valves 45 opening outward from the cylinder 24^a. With this arrangement, excessive pressure developed by the compression in the cylinder 24 will be vented into the pressure-supply. It not only limits the 40 pressure of compression, but automatically adjusts or regulates this pressure in such a way that when the pressure in the air-supply drops, the compression-pressure will be correspondingly reduced; or conversely, when 45 the pressure-supply goes up, the compression-pressure goes up in the same proportion and so adjusts the compression automatically to suit variations in the pressure-supply. The 50 passages 44 need not necessarily lead to the pressure-supply. They may be arranged to exhaust into the atmosphere, and in this event by properly adjusting the springs back of the valves 45, said valves may be made to automatically limit the compression-pressure 55 to any desired degree, thus furnishing

another means for controlling the resistance offered by compression to the movement of the actuating piston.

If desired, instead of providing the chambers 40 and valves 42, the ends of the cylinder 24 or 24^a may be placed in communication with chambers having movable walls backed by yielding elements or by the compressed air supply or by a combination of the two, these devices forming variable clearance 70 spaces, which automatically enlarge or contract, according to the compression-pressure in the cylinder 24 or 24^a, these devices taking the place of said chambers 40 in regulating, adjusting or controlling said compression- 75 pressure.

By the devices herein described we are enabled instantly to bring to bear on the valve a forceful actuating pressure, moving the valve quickly over its stroke and arresting 80 the valve promptly yet without knocks or jars, and this result is attained by less mechanism and with the expenditure of less energy than devices heretofore devised.

Having thus described the preferred form 90 of our invention, what we claim as new and desire to secure by Letters Patent is:

1. In a valve mechanism, the combination with a valve, of a cylinder having admission and exhaust ports located intermediate its 95 ends, a double acting actuator piston in the cylinder having ports extending from its heads inward to the side of the piston at a point intermediate its heads, means for controlling fluid pressure movements in the ports 100 of the cylinder, and means establishing a connection between the actuator piston and the valve.

2. In a valve mechanism, the combination with a valve, of a cylinder having admission 105 and exhaust ports intermediate its ends, a double acting actuator piston in the cylinder, the piston having ports extending from its heads inward to the side of the piston intermediate the heads, a pilot valve and casing adapted to control the fluid movement 110 through the admission and exhaust ports of the cylinder, and means establishing a connection between the actuator piston and valve.

3. In a valve mechanism, the combination with a valve, of a cylinder having an admission and an exhaust port adjacent to each end thereof, a double acting actuator piston in the cylinder having two ports leading respectively from the piston heads to the side of the piston at points intermediate the heads thereof, the ports of the piston being adapted respectively to register with the admission ports of the cylinder, a means for controlling 120 fluid movement through the ports of the cylinder, and a means establishing connection between the actuator piston and valve.

4. In a valve mechanism, the combination with a valve, of a cylinder having an admis- 130

sion and an exhaust port adjacent to each end thereof, a double acting actuator piston in the cylinder having two ports leading respectively from the piston heads to the side 5 of the piston at points intermediate the heads thereof, the ports of the piston being adapted respectively to register with the admission ports of the cylinder, a pilot valve and casing, the latter communicating with 10 the ports of the cylinder and the former being adapted alternately to uncover the admission ports of the cylinder and the exhaust ports respectively opposed thereto, and a means establishing connection between the actuator 15 piston and the valve.

5. A valve mechanism comprising the combination with a valve, of a cylinder having admission and exhaust ports respectively adjacent to its ends, a double acting actuator 20 piston in the cylinder, the piston having ports leading from its heads inward to the side of the piston at points intermediate its ends, the ports of the piston being adapted respectively to register with the admission 25 ports of the cylinder, a valve casing communicating with the cylinder ports and having an intermediately situate pressure supply port and exhaust ports at opposite sides thereof, a pilot valve operating within the 30 casing and comprising two piston valve parts connected by a reduced distance piece or spacer, the said piston valve parts coacting respectively with the admission and exhaust ports at the cylinder end portions and being 35 adapted alternately to uncover the admission ports and the exhaust ports respectively opposed thereto, and a means establishing connection between the actuator piston and valve.

40. 6. A valve mechanism comprising the combination with a valve, of a cylinder having two admission ports located intermediate of but respectively adjacent to its ends, the cylinder also having exhaust ports respectively 45 adjacent to its ends, a double acting actuator piston in the cylinder, the piston having ports leading respectively from its heads to the side of the piston at points intermediate its ends, the ports of the piston being adapted 50 respectively to register with the admission ports of the cylinder, a means controlling fluid movement through the cylinder admission ports, and means establishing a connection between the actuator piston and 55 the valve.

7. The combination of a cylinder having two admission ports located intermediate of but respectively adjacent to its ends, the cylinder also having exhaust ports respectively 60 adjacent to its end portions, a double acting piston operating in the cylinder and having ports therein leading from its ends or heads inward to the side of the piston intermediate its ends, the piston ports registering 65 with the cylinder admission ports corre-

sponding thereto alternately as the piston approaches its ends of travel, and the piston alternately moving its ends past the exhaust ports corresponding thereto as the piston approaches its end of travel, and means controlling fluid movement through the cylinder admission ports.

8. The combination of a cylinder having two admission ports located intermediate of but respectively adjacent to its ends, the cylinder also having exhaust ports respectively 70 adjacent to its end portions, a double acting piston operating in the cylinder and having ports therein leading from its ends or heads inward to the side of the piston intermediate 75 its ends, the piston ports registering with the cylinder admission ports corresponding thereto alternately as the piston approaches its ends of travel, and the piston alternately moving its ends past the exhaust ports corresponding thereto as the piston approaches its end of travel, means controlling fluid movement through the cylinder admission ports, a valve, and means establishing a connection between the valve and piston to actuate the 80 former from the latter.

9. The combination of a cylinder having two admission ports located intermediate of but respectively adjacent to its ends, the cylinder also having exhaust ports respectively 85 adjacent to its end portions, a double acting piston operating in the cylinder and having ports therein leading from its ends or heads inward to the side of the piston intermediate 90 its ends, the piston ports registering with the cylinder admission ports corresponding thereto alternately as the piston approaches its ends of travel, and the piston alternately moving its ends past the exhaust ports corresponding thereto as the piston approaches its end of travel, means controlling fluid movement through the cylinder admission ports, a valve, and means establishing a connection between the valve and piston to actuate the 95 former from the latter.

10. The combination of a cylinder, a piston therein, a means for exerting a fluid pressure on one side of the piston and for developing a fluid compression on the other side of the piston, a means adapted to establish communication between said other side of the piston and the source of fluid pressure, and a yieldingly seated check valve commanding said communication and opening 110 toward the source of fluid pressure.

11. The combination of a cylinder, a piston therein, means for exerting a fluid pressure on one side of the piston and for developing a fluid compression on the other side 115 120 125 130

- of the piston, a means adapted to establish communication between said other side of the piston and the source of fluid pressure, and an automatic device normally closing 5 said communication and opening upon the development of a predetermined compression.
12. The combination of a cylinder, a piston, devices for exerting a fluid pressure on one side of the piston to move the piston in 10 one direction, and for developing a fluid compression resisting the piston movement, a means adapted to establish communication between the source of fluid pressure and said 15 fluid compression, and a device normally closing said communication and opening upon the development of a predetermined compression.
13. The combination of a cylinder, an actuator piston therein, means for admitting and exhausting pressure to and from the cylinder to move the piston and develop a fluid cushion to bring the piston to rest, additional means adapted to establish 20 communication between the parts of the cylinder in which the fluid cushion is developed and the source of fluid pressure, and an automatic device controlling said communication and opening upon the said cushion 25 reaching a pre-determined pressure.
14. The combination of a cylinder, an actuator piston therein, means for admitting and exhausting pressure to and from the cylinder to move the piston and develop a fluid cushion to bring the piston to rest, additional means adapted to establish 30 communication between the part of the cylinder in which the fluid cushion is developed and the source of fluid pressure, and an automatic device controlling said communication and opening upon the said cushion 35 reaching a predetermined pressure.
15. The combination of a cylinder, an actuator piston therein, means for admitting and exhausting pressure to and from the cylinder to move the piston and develop a fluid cushion to bring the piston to rest, additional means adapted to establish 40 communication between the part of the cylinder in which the fluid cushion is developed and the source of fluid pressure, an automatic device controlling said communication and opening upon the said cushion 45 reaching a predetermined pressure, and walls forming an auxiliary chamber communicating with the part of the cylinder in which the cushion is formed.
16. The combination of a cylinder, an actuator piston therein, means for admitting and exhausting pressure to and from the cylinder to move the piston and develop a fluid cushion to bring the piston to rest, additional means adapted to establish 50 communication between the part of the cylinder in which the fluid cushion is developed and the source of fluid pressure, an automatic device controlling said communication and opening upon the said cushion reaching a predetermined pressure, and walls forming an auxiliary chamber communicating with the part of the cylinder in which the cushion is formed.
- in which the fluid cushion is developed and 65 the source of fluid pressure, an automatic device controlling said communication and opening upon the said cushion reaching a predetermined pressure, walls forming an auxiliary chamber communicating with the 70 part of the cylinder in which the cushion is formed, and means controlling said communication between the said auxiliary chamber and the cylinder.
17. The combination of a piston rod, a valve surrounding the same, a valve housing through which the rod passes, a valve stem mounted in the housing to sustain the valve by the housing, and fluid pressure operated 75 devices carried by the housing and having 80 connection with the valve to operate the same.
18. The combination of a piston rod a valve housing through which the rod passes, a valve encircling the rod and sustained by 85 the housing, and fluid pressure operating devices also sustained by the housing for actuating the valve.
19. The combination of a piston rod a valve housing through which the rod passes, 90 a valve, a valve stem mounted in the housing the valve and stem encircling the piston rod, a fluid pressure actuated means sustained by the housing, and a connection between the valve and said means to operate 95 the valve.
20. The combination of a rod, a valve encircling the same, a valve housing, fluid pressure actuated means sustained by the housing, and a connection between said means 100 and the valve.
21. The combination of a rod, a valve encircling the same, a tubular valve stem also encircling the rod, a valve housing in which the valve is mounted, fluid pressure actuated 105 devices sustained by the housing, and a connection between said devices and the valve.
22. The combination of a rod, a valve encircling the same, a tubular valve stem also 110 encircling the rod, a valve housing having an outer and inner shell, the housing encircling the rod, and the valve-stem being mounted in the inner shell of the housing, means attached to the housing for operating 115 the valve, and a connection between the said means and the valve, the connection extending between the inner and outer shells of the housing.
23. The combination of a rod, a valve encircling the same, a tubular valve-stem also encircling the rod, a housing encircling the rod and comprising an inner and outer shell, a packing acting between the inner shell and the rod, the valve-stem operating 120 in the inner shell, a packing acting between the valve-stem and the said inner shell, a means for operating the valve, and a rod 125

connecting the valve with said means and extending between the housing and the shells thereof.

24. The combination of a cylinder, a double-acting piston operating therein, and means for bringing about a reciprocation of the piston by fluid-pressure, said means including devices for developing an increasing fluid-compression resisting each movement 10 of the piston and for relieving said compression at or near the time when the piston has been brought to rest.

25. In a valve mechanism, the combination with the valve, of a cylinder, a double-acting piston in the cylinder, a connection 15 between the piston and valve, and means for bringing about the reciprocation of the piston by fluid-pressure, said means including devices for developing an increasing fluid 20 compression resisting each movement of the piston and for relieving said compression at or near the time when the piston has been brought to rest.

26. The combination of a rod, a valve 25 encircling the same, a tubular valve-stem also encircling the rod, a housing encircling the rod and comprising an inner and outer shell, a packing acting between the inner shell and the rod, the valve-stem operating in the inner shell, a packing acting between the valve- 30 stem and said inner shell, a means for operating the valve, and a rod connecting the valve with said means and extending between the housing and the shells thereof, the said 35 means for operating the valve being mounted on and sustained by the housing.

27. The combination of a valve, an actuator piston, a mechanical connection between the valve and piston, a casing in which the 40 piston works, said piston having ports leading from its heads inward to the sides of the piston and the casing having near each end an admission and exhaust port, the ports of the piston being adapted under certain piston 45 positions to register with the adjacent admission and exhaust ports of the casing, and means for controlling the fluid movement through the casing ports, said ports acting to oppose to the movement of the valve and piston 50 ton a fluid compression to bring the valve and piston to rest.

28. The combination of a valve, an actuator piston, a mechanical connection between the valve and piston, a casing in which 55 the piston works, said piston having ports leading from its heads inward to the sides of the piston and the casing having near each end an admission and exhaust port, the ports of the piston being adapted under certain 60 piston positions to register with the adjacent admission and exhaust ports of the casing, and means for controlling the fluid movement through the casing ports, said ports acting to oppose to the movement of the valve and piston 65 ton a fluid compression to bring the valve

and piston to rest, and to relieve said compression when the valve and piston are brought to rest.

29. The combination of a valve, an actuator piston, a connection between the valve and piston, a casing in which the piston operates, the casing having near each end admission and exhaust ports, and the piston having a port in each end the ports running to the side of the piston, and said piston ports 75 registering with the two casing ports respectively adjacent when the piston is in its end positions, and a means controlling fluid movement through the casing ports whereby a fluid cushion is opposed to the movement 80 of the piston and valve to check said movement.

30. The combination of a valve, an actuator piston, a connection between the valve and piston, a casing in which the piston operates, the casing having near each end admission and exhaust ports, and the piston having a port in each end the ports running to the side of the piston, and said piston ports 85 registering with the two casing ports 90 respectively adjacent when the piston is in its end position, and a means controlling fluid movement through the casing ports whereby a fluid cushion is opposed to the movement of the piston and valve to check 95 said movement, and said means controlling fluid movement acting to uncover the casing exhaust ports when the corresponding piston ports register therewith, whereby to relieve said cushion when the valve has been brought 100 to rest.

31. The combination of an actuator piston, a casing in which the piston operates, the casing having near each end admission and exhaust ports, and the piston having a 105 port in each end the ports running to the side of the piston, and said piston ports registering with the two casing ports respectively adjacent when the piston is in its end positions, a means controlling fluid movement through 110 the casing ports whereby a fluid cushion is opposed to the movement of the piston and valve to check said movement, a valve, and a mechanical connection between the valve and piston.

32. The combination of an actuator piston, a casing in which the piston operates, the casing having near each end admission and exhaust ports, and the piston having a port in each end the ports running to the side of the piston, and said piston ports registering with the two casing ports respectively adjacent when the piston is in its end position, a means controlling fluid movement through the casing ports whereby a fluid cushion is 125 opposed to the movement of the piston and valve to check said movement, and said means controlling fluid movement acting to uncover the casing exhaust ports when the corresponding piston ports register there- 130

with, whereby to relieve said cushion when the valve has been brought to rest, a valve, and a mechanical connection between the valve and piston.

5 33. The combination of a piston rod, a valve encircling the same, an actuator piston, a mechanical connection between the piston and valve, a casing in which the piston operates, the casing having admission and exhaust ports near each end, and the piston having a port in each end running to the side of the piston and adapted to register respectively with the casing ports adjacent, and means controlling fluid movement through 10 the casing ports.

15 34. The combination of a piston rod, a valve encircling the same, an actuator piston, a mechanical connection between the piston and valve, a casing in which the piston operates, the casing having admission and exhaust ports near each end, and the piston having a port in each end running to the side of the piston and adapted to register respectively with the casing ports adjacent, means 20 controlling fluid movement through the casing ports, and a valve housing through which the piston rod passes, said housing supporting the said casing.

25 35. The combination of a piston rod, a valve encircling the same, an actuator piston, a mechanical connection between the piston and valve, a casing in which the piston operates, the casing having admission and exhaust ports near each end, and the piston having a port in each end running to the side of the piston and adapted to register respectively with the casing ports adjacent, and means 30 controlling fluid movement through the casing ports, the piston ports being arranged to register with the casing admission and exhaust ports respectively adjacent when the piston is in its end positions, and the said means controlling fluid movement being arranged to uncover the casing 35 exhaust ports when they are in registry with the piston ports whereby to oppose a fluid cushion to the movement of the piston and valve and to relieve the cushion when said parts have been brought to rest.

40 36. The combination of a piston rod, a circular valve surrounding the same, a valve housing through which the rod runs and in which the valve is arranged, a cylinder supported by the housing, an actuator piston in the cylinder, a rod connecting the piston and valve, the rod passing through the housing, and means controlling the application of fluid pressure to the piston to operate the valve.

45 37. The combination of a piston rod, a circular valve surrounding the same, a valve housing through which the rod runs and in which the valve is arranged, a cylinder supported by the housing, an actuator piston in the cylinder, a rod connecting the piston and

valve, the rod passing through the housing, and means controlling the application of fluid pressure to the piston to operate the valve, the piston and casing being ported and coacting with said means controlling the application of fluid pressure whereby to oppose a fluid cushion to the piston movement to bring the piston and valve to rest and to relieve said cushion when the valve has been brought to rest. 75

38. The combination of a piston rod, a valve housing inclosing the same, a circular valve surrounding the piston rod, a tubular valve stem loosely inclosing the piston rod, and mounted and sustained in the housing, 80 and means for operating the valve.

39. The combination of a piston rod, a valve housing inclosing the same and comprising inner and outer tubular walls connected by a web, a circular valve surrounding the 85 rod, a tubular valve stem loosely inclosing the rod, and fitted and sustained in the inner wall of the housing, and means for operating the valve.

40. The combination of a piston rod, a valve housing inclosing the same and comprising inner and outer tubular walls connected by a web, a circular valve surrounding the rod, a tubular valve stem loosely inclosing the rod, and fitted and sustained in the inner 90 wall of the housing, and means for operating the valve, the means for operating the valve including a rod extending through the housing between its walls. 95

41. The combination of a piston rod, a valve housing inclosing the same and comprising inner and outer tubular walls connected by a web, a circular valve surrounding the rod, a tubular valve stem loosely inclosing the rod, and fitted and sustained in the inner 100 wall of the housing, means for operating the valve, and a packing acting between the rod and the inner housing wall at a point outward from the valve stem. 105

42. The combination of a rod, a valve housing inclosing the same, a valve surrounding the rod but out of contact therewith, and a tubular valve stem also surrounding the rod out of contact therewith and engaged with the housing to sustain the valve and 110 stem independently of the rod. 115

43. The combination of a rod, a valve housing inclosing the same and having inner and outer tubular walls, a valve commanding the passage within the walls of the housing and loosely surrounding the rod, and a tubular valve stem loosely surrounding the rod and engaged with the inner tubular walls of the housing to sustain the valve and stem independently of the rod. 120 125

44. The combination of a rod, a valve housing inclosing the same and having inner and outer tubular walls, a valve commanding the passage between the walls of the housing and loosely surrounding the rod, a tubular 130

valve stem loosely surrounding the rod and engaged with the inner tubular wall of the housing to sustain the valve and stem independently of the rod, said stem being fitted 5 within said inner wall, and a skirt connected with the valve and loosely surrounding the adjacent end of the said inner wall, for the purpose specified.

45. The combination of a rod, a valve 10 housing inclosing the same and having inner and outer tubular walls, a valve commanding the passage within the walls of the housing and loosely surrounding the rod, a tubular valve stem loosely surrounding the rod and 15 engaged with the inner tubular walls of the housing to sustain the valve and stem independently of the rod, said stem being fitted within said inner wall, a packing acting between the wall and stem, and a packing acting 20 between the said wall and the rod at the end of the wall opposite the valve, the second packing being removable to give access to the first packing.

46. The combination of a reciprocal rod, a 25 valve housing surrounding the same, a cylinder juxtaposed to the housing, an actuator piston in the cylinder, a valve, a mechanical connection between the piston and valve, and means controlling the application of 30 fluid pressure to the piston.

47. The combination of a reciprocal rod, a valve housing surrounding the same, a cylinder juxtaposed to the housing, an actuator piston in the cylinder, a valve, a mechanical 35 connection between the piston and valve, and means controlling the application of fluid pressure to the piston, said means including an operating element moving in synchronism with the rod.

40 48. The combination of a reciprocal rod, a valve housing surrounding the same, a cylinder sustained by the housing, an actuator piston in the cylinder, a valve, a mechanical connection between the piston and valve, 45 and means controlling the application of fluid pressure to the piston.

49. The combination of a reciprocal rod, a housing surrounding the rod, a valve coacting with the housing and surrounding the rod, a 50 cylinder attached to the housing, a piston in the cylinder, a rod connected to the piston and valve to actuate the latter from the former, and means controlling the application of pressure to the piston to operate the 55 same.

50. The combination of a reciprocal rod, a housing surrounding the rod, a valve coacting with the housing and surrounding the rod, a cylinder attached to the housing, a piston 60 ton in the cylinder, a rod connected to the piston and valve to actuate the latter from the former, and means controlling the application of pressure to the piston to operate the same, said means including an actuating 65 element moving in synchronism with the rod.

51. The combination of a reciprocal rod, a housing surrounding the rod, a valve coacting with the housing and surrounding the rod, a cylinder attached to the housing, a piston in the cylinder, a rod connected to the piston and valve to actuate the latter from the former, and means controlling the application of pressure to the piston to operate the same, the valve and cylinder being located at opposite ends of the housing and the second 70 named rod extending through the housing. 75

52. The combination of a reciprocal rod, a housing surrounding the same and having inner and outer tubular walls connected at one end by a web, a circular valve encircling 80 the rod and coacting with the other end of the housing, a tubular stem loosely surrounding the rod and engaging the inner wall of the housing, a cylinder attached to the housing at the end opposite the valve, a piston in the 85 cylinder, a rod attached to the valve and cylinder and extending through the housing between the two walls thereof, and means controlling the application of fluid pressure to the piston. 90

53. The combination of a valve, an actuator member, a mechanical connection between the valve and member to move the valve from the member, means for exerting a force on the member to move it from one position to another, and means for exerting on the member an increasing opposing force during the exertion of the first named force to bring the member gradually to rest, and for relieving said opposing force prior to the 100 termination of the first force to hold the member in its new position.

54. The combination of a valve, an actuator member, a mechanical connection between the valve and member to move the 105 valve from the member, means for exerting fluid pressure on the member to move it from one position to another, and means for exerting on the member an increasing opposing fluid pressure during the exertion of the first 110 named fluid pressure to bring the member gradually to rest, and for relieving said opposing fluid pressure prior to the termination of the first fluid pressure to hold the member in its new position. 115

55. The combination of a valve, an actuator member, a mechanical connection between the two to actuate the former from the latter, means for exerting on the actuator member a decreasing force to move the member from one position to another, and means for exerting on the member an increasing opposing force during the exertion of the first named force to bring the member gradually to rest and for relieving said opposing force 125 prior to the termination of the first named force to hold the member in its new position.

56. The combination of a valve, an actuator member, a mechanical connection between the two to actuate the former from the 130

latter, means for exerting on the actuator member a decreasing fluid pressure to move the member from one position to another, and means for exerting on the member an increasing opposing fluid pressure during the exertion of the first named fluid pressure to bring the member gradually to rest and for relieving said opposing fluid pressure prior to the termination of the first named fluid pressure to hold the member in its new position.

57. The combination of a valve, an actuator piston, a mechanical connection between the piston and the valve, said piston having a port in each end, the ports extending inward to the side of the piston intermediate its ends, a casing in which the piston operates, the casing having adjacent to each end admission and exhaust ports, and said piston being arranged to move its ends past the respective exhaust ports to uncover the same, and the ports in the piston being capable of registry with both the admission and

exhaust ports respectively adjacent thereto, and a pilot valve controlling fluid movement through the casing ports whereby fluid pressure is exerted on the actuator piston to move it from one position to another, and simultaneously an increasing fluid compression is opposed to the piston movement, said opposing fluid pressure being relieved prior to the termination of the first named fluid pressure when the part in the end of the piston at which the compression exists registers with the corresponding casing exhaust port, thereby holding the actuator piston and valve in the new position.
